UNITED STATES PATENT OFFICE.

GEORGE P. BOSWORTH, OF CENTRAL FALLS, RHODE ISLAND, ASSIGNOR TO HEMPHILL COMPANY, OF CENTRAL FALLS, RHODE ISLAND, A CORPORATION OF MASSACHUSETTS.

SPRING NEEDLE PRESSER.

Application filed May 26, 1919. Serial No. 299,972.

To all whom it may concern:

Be it known that I, GEORGE P. Bosworth, a citizen of the United States, and a resident of Central Falls, in the county of Providence and State of Rhode Island, have invented an Improvement in Spring Needle Pressers, of which the following description, in connection with the accompanying drawings, is a specification, like characters on the drawings representing like parts.

This invention relates to spring needle pressers, and it is the object thereof to provide individual needle pressers capable of being produced in large numbers, accurately and with a substantial uniformity in the articles so produced.

The invention consists of certain features pertaining to the presser whereby the above objects may be attained, as set forth in the following specification and particularly pointed out in the claims.

Referring to the drawings wherein I have, merely for illustrative purposes, disclosed a presser embodying the features of my invention, together with instrumentalities for effecting the grinding thereof,

Fig. 1 is an enlarged end elevation of means for holding a group of pressers during the grinding operations;

Fig. 2 is a section taken on the line 2—2 of Fig. 1 and illustrates one method of applying the grinding instrument to the surfaces to be ground;

Fig. 3 is a side elevation greatly enlarged of one of the pressers embodying this invention, a spring beard needle being shown in connection therewith, the beard whereof is unpressed, as shown in full lines, and pressed into the eye of the needle, as shown in dotted lines, so as to illustrate the manner in which a needle and its presser cooperate to form a loop;

Fig. 4 is an end view of the presser and of a knitting needle shown in their cooperative relation;

Fig. 5 is a detail view illustrating another form of grinder that may be used in grinding the needle-beard engaging surfaces of said pressers;

Fig. 6 is a plan view of a section of a presser holding cage with a number of pressers mounted therein in knitting relation;

Fig. 7 is a plan view of a portion of a circular series of pressers arranged in grinding relation; and

Fig. 8 is a greatly enlarged plan view of a presser embodying the invention.

Although the present invention is applicable to various types of individual pressers, I have elected, merely for convenience, to show the same in connection with the presser disclosed in my Patent No. 1,209,256, dated Dec. 19, 1916.

This type of presser, as most clearly shown in Figs. 3 and 4, embodies a head portion 1 of slightly greater thickness than the knitting needle 2 with which it is to cooperate. This head 1 has a beard-engaging surface 3 adapted at certain times in the knitting operations, and by means of a suitable presser cam not shown, to be moved into a position to engage the beard 4 of the needle during the loop-forming movement thereof in order to press said beard into the needle eye 5.

The upper portion of the head 1 of said presser is inclined or beveled at 6 sufficiently to prevent the end of the beard 4 from abutting against the upper end of said presser during said loop-forming movement and to effect the deflection of the beard 4 thereof into its eye at a time when said presser has been moved by said presser cam into its beard-engaging position, as shown most clearly in Fig. 3.

The type of presser shown herein has a relatively thin depending stem portion 7 adapted to fit into a corresponding slot formed in the outer face of a retaining or assembling ring 8 shown most clearly in Fig. 6, into which ring the desired number of pressers are placed at suitable distances apart and wherein they are held by appropriate means not shown.

As shown in Fig. 3, the lower end of the stem 7 of each presser is made tapering, it being beveled both at the front and back edges thereof, the front bevel being especially provided for the purpose of allowing a slight rocking movement of the presser to be effected in the ring 8 by the presser cams during the movement thereof from their inactive to their pressing positions. The back beveled surface which extends from the lower end of the stem 7 to the notch 11 is merely for the purpose of facilitating the assembling of the pressers in the retaining ring 8.

This invention is principally concerned with the form of the beard engaging faces

3 and 6 of the pressers which are herein shown concavely ground with the grinding lines extending transversely of said faces.

Obviously the curvature of the concave face 3, shown most clearly in Fig. 8, may be varied according to the degree of curvature desired but whatever this radius may be it preferably will always describe a segment of a true circle and its center will coincide with the center of the circle described by the beard-engaging faces of the pressers when arranged for grinding. In other words these segments of a circle collectively describe a continuous or true circle, the radius whereof coincides with the radius of said segment when the pressers are grouped for grinding. This will be more clearly understood by referring to Fig. 7 wherein the radius of the inner face 3 is indicated at A and corresponds with the radius A of the enlarged Fig. 8.

By forming the pressers with transversely ground concave beard-engaging faces a number of advantages will result which advantages include the use of a very simple form of holder such, for example, as I have illustrated in Figs. 1 and 2. This holder comprises a member 12 having an arbor 13 for insertion in a lathe chuck or the like. Formed in a cylindrical part 14 of the member 12 are closely spaced peripheral grooves 15 adapted to receive the stems 7 of the pressers which rest with their shoulders 7 against the ends 16 of said cylindrical part 15 wherein they are yieldingly held during assembling, by a spring band 17 resting in a groove 14' in said part 14. The slots 15 are arranged close enough together to insure the touching of the edges of the thickened heads of the pressers wherein the grooves 3 and 6 are formed whereby a substantially continuous circle will be formed, the radius whereof substantially coincides with the radius A of Fig. 7.

A collar 18 is adapted to fit over the part 14 encircling the pressers arranged in said grooves and is firmly held by screw threads 19 and 20 with a shoulder 21 thereof seating against shoulders 22 on the pressers, said collar bearing at 23 against the straight outer edges 24 of said presser. An internal face 25 of said shoulder 21 also engages edges 26 of said pressers serving to provide suitable backing for said pressers during the grinding operations.

With the pressers thus firmly held in circular arrangement with each side of the inner edge of the thickened head of each presser engaging the corresponding sides of adjacent pressers, the grinding of the edges 3 and 6 may be effected without producing any rough edges or burrs thereon by means of a single appropriately formed grinder such for example, as shown at 27 in Fig. 4 or at 29 Fig. 5 which operates trans-

versely of said edges during relative or concurrent movements of said pressers and grinder in opposite directions to produce concavities that are precisely alike or uniform in all of the pressers.

A comparison of Figs. 6 and 7 will disclose the fact that the radius B of the circle described by the faces 3 of the circular series of pressers, when arranged in the ring 8 for knitting, is much larger than the radius A of the circle of said pressers when the latter are arranged in the holder grooves 15 for grinding.

Claims:

1. As an article of manufacture, a needle beard presser having a ground, beard-depressing surface, the grinding lines whereof extend transversely to the direction of movement of the needle beard during the depressing operations.

2. As an article of manufacture, an individual needle beard presser having a transversely ground, beard-engaging surface.

3. As an article of manufacture, an individual needle beard presser having a transversely ground, concave, beard-engaging surface.

4. As an article of manufacture, an individual needle beard presser having a concavely ground, beard-deflecting surface the concaved face of said presser describing a segment of a true circle formed in transversely grinding said surface.

5. As an article of manufacture, a needle beard presser having a transversely ground, concave, beard-deflecting surface extending longitudinally of the head portion of said presser.

6. As an article of manufacture, an individual needle beard presser having a beard-engaging head, and a relatively thin stem, said head having relatively inclined, ground, concave, beard-engaging edges, the grinding lines whereof extend transversely of said head.

7. As an article of manufacture, an individual needle beard presser adapted for arrangement in a circular series for knitting, said presser having a transversely ground concaved beard engaging surface, the radius whereof is shorter than the radius of the circle described by said circular series of pressers.

8. A circular series of spaced, individual needle beard pressers each having a ground concaved beard engaging face describing a segment of a circle, the radius whereof coincides with the radius of the circle described by said circular series when the latter are arranged with the edges of their beard engaging faces in substantial contact, said grinding being transverse.

9. A circular series of spaced, individual, needle beard pressers each having a transversely ground, concaved, beard-engaging

face, the concavities of the entire series of 5
pressers being identical and the longitudinal edges of said pressers being devoid of roughness, the radius of the concavity of each presser being shorter than the radius of the circle described by said circular series when said pressers are spaced for knitting.

10. A circular series of spaced, individual, needle beard pressers, each having a trans- 10
versely ground, concaved, beard-engaging face, the concavities of the entire set of pressers being identical, and the radius of said concavities co-extending with the radius of the circle described by said circular series 15
of pressers when the latter are arranged with the edges of their beard-engaging faces in substantial contact when said pressers are grouped for finishing.

11. As an article of manufacture, an individual, needle beard presser having a trans- 20

versely ground, beard-deflecting surface extending longitudinally of the head portion of said presser, said concavity comprehending the entire surface of said head portion and the longitudinal edges defining said concavity being wholly devoid of roughness owing to said transversely ground concavity. 25

12. A circular series of individual needle beard pressers each having a thickened concave beard-engaging face with grinding 30
marks extending transversely of said face, the concave faces of said pressers being constructed, when in grinding relation, collectively to describe a continuous circle with a radius coinciding with the radius of the concave face of each of said pressers. 35

In testimony whereof, I have signed my name to this specification.

GEORGE P. BOSWORTH.
